UNITED STATES PATENT OFFICE.

LOUIS H. AYRES, OF PHILADELPHIA, PENNSYLVANIA, ASSIGNOR TO HIMSELF, WILLIAM M. AYERS, WILLIAM G. AYERS, AND GEORGE R. AYERS, OF PHILADELPHIA, PENNSYLVANIA, TRADING UNDER THE FIRM-NAME OF WILLIAM AYERS AND SONS.

HORSE-BLANKET.

SPECIFICATION forming part of Letters Patent No. 749,514, dated January 12, 1904.

Application filed July 24, 1903. Serial No. 166,880. (No model.)

To all whom it may concern:

Be it known that I, LOUIS H. AYRES, a citizen of the United States, residing in Philadelphia, Pennsylvania, have invented certain Im- 5 provements in Horse-Blankets, of which the following is a specification.

The object of my invention is to so construct a horse-blanket that the same will present an attractive external appearance and will be 10 strong enough to provide the proper support for the straps whereby it is secured upon the body of a horse and yet will permit such free circulation of air adjacent to the body of the horse as to dry the same when it is wet from 15 perspiration, while at the same time the rapid radiation of heat from the surface of the body is arrested and the chilling of said surface thereby prevented.

In the accompanying drawings, Figure 1 is 20 a side view of a horse-blanket constructed in accordance with my invention and showing one corner of the same turned up in order to expose the lining or inner surface of the blanket; and Fig. 2 is an exaggerated section of the 25 blanket, illustrating the fabrics of which the same is composed.

My improved horse-blanket is composed of an outer and closely-woven fabric 1, of cotton, wool, or other available material, and an inner and more loosely-woven fabric 2, of burlap or other coarse and loosely-woven fabric, these two fabrics being secured together by stitches around the borders of the blanket and at such other points as may be necessary. The 35 outer closely-woven fabric 1 can have any desired pattern produced thereon either in the weaving of the fabric, by subsequent printing, or by other means, and this closely-woven fabric is sufficiently firm and strong to provide 40 the proper support for the straps 3, 4, and 5 and for the neck-fastenings 6, with which horse-blankets are usually provided, while the inner

fabric 2, owing to its coarse texture, provides channels for the circulation of air adjacent to the body of the horse, and thus permits of the 45 drying of said surface when the same is wet with perspiration, the close texture of the outer fabric 1, however, retaining the natural heat of the body and preventing the objectionable chilling of the same, which is caused if 50 such heat can be freely radiated through the blanket. The inner surface of the fabric may be brushed, if desired, to form a fleece thereon, and thus provide a softer surface for contact with the body of the horse than would be presented by the comparatively harsh threads of 55 which said fabric is composed; but such fleecing of the inner face of said fabric does not obstruct the circulation of air between the two fabrics due to the coarseness or openness of 60 weave of said inner fabric.

Having thus described my invention, I claim and desire to secure by Letters Patent—

1. A horse-blanket composed of inner and 65 outer textile fabrics secured together, the inner fabric being of coarser or more open texture than the outer fabric, substantially as specified.

2. A horse-blanket composed of inner and 70 outer textile fabrics secured together around the borders of the blanket and where straps and other fastenings are applied to the blanket, but otherwise free from connection with each other, the inner fabric being of coarser 75 or more open texture than the outer fabric, substantially as specified.

In testimony whereof I have signed my name to this specification in the presence of two subscribing witnesses.

LOUIS H. AYRES.
